UNITED STATES PATENT OFFICE.

CHARLES EDWARD BLYTH, OF STOCKTON, NEAR RUGBY, ENGLAND, ASSIGNOR TO
ALFRED HERBERT LIMITED, OF BUTTS, COVENTRY, ENGLAND, A BRITISH COMPANY.

COAL-PULVERIZING MACHINE.

Application filed April 13, 1926, Serial No. 101,805, and in Great Britain May 16, 1925.

This invention relates to coal and similar pulverizing machines, of the type shown in my prior patent Reissue No. 16,229, in which a stream of air passing through the machine 5 carries the finely powdered coal in suspension, whilst means are provided to return to the pulverizing chamber such particles of coal as have not attained a sufficient degree of fineness, and its object is to provide mechanism for this purpose which will be effective and inexpensive as well as easy to renew if necessary.

In such apparatus, a rotor disk is mounted centrally of the casing between an inlet for 15 air and coarse material and a centrally located outlet to provide two pulverizing zones which communicate annularly around the periphery of the rotor. The disk is provided with rows of pegs on each side which 20 interfit and cooperate with rows of stationary pegs on the two opposed casing walls. The coarse material is ground preliminarily in the inlet zone and is then drawn by a fan adjacent the outlet around the disk and into 25 the final pulverizing zone. Here the material must be subjected to the impacts of the rapidly revolving pegs on the rotor as it is drawn inwardly towards the centrally located outlet.

According to this invention, in the exit 30 from the pulverizing chamber is employed a rejector device constituted by one or more rotating members adapted to traverse the outgoing stream and to throw back into the 35 pulverizing mechanism the heavier particles of coal. Thus until such particles attain the necessary degree of fineness they are repeatedly returned into the pulverizer for further treatment.

A ring adapted to guide the path of the 40 rejected particles may also be provided to increase the effectiveness of the rejector device in returning the larger coal particles to the pulverizer mechanism.

In the accompanying drawings, illustrating 45 the application of the invention to a known kind of pulverizing machine,

Figure 1 is a diagrammatic sectional view of the machine,

Figure 2 is a fragmentary view of a part 50 of the machine showing one form of rejector device, to a larger scale than Figure 1, and

Figure 3 is an end view of Figure 2.

The machine shown diagrammatically in Figure 1 comprises a pulverizing chamber 2, having fixed beaters 3 and rotating beaters 4 carried by a main shaft 5 on which also is mounted a fan (not shown) located in a casing 6 beside the pulverizer chamber.

Coal is fed through the passage 7 and at the lower part 8 encounters an upward draught of air created by the fan, which sweeps it through the branch 9 into the pulverizing chamber 2, from which it passes eventually by way of a central exit aperture 10 into the fan casing, and thence to the burner.

It is at this exit aperture 10 that it is important not only to prevent the discharge 70 of such particles of coal as are not sufficiently reduced in size, but also to provide for their return to the pulverizing chamber for further treatment.

Accordingly, therefore, the rejector device 75 is a rotating striker in the form of a radially arranged blade mounted upon the main shaft 5 or the hub 12 of the rotating part of the pulverizer.

The shape of the blade may be such that 80 its root 13 is in the plane of the exit aperture 10, this being provided in a diaphragm plate 14 dividing the pulverizing chamber from the fan chamber, whilst the tip 15 of the blade is within the pulverizing chamber 85 itself. A screen or guide ring 16 may be arranged around the edge of the exit aperture on the side towards the pulverizer, so that the tip of the blade is within the ring. The inner face of the ring may be flared or 90 belled outwardly, as at 17, towards the pulverizing chamber, and this serves to guide back into the latter the heavier particles of coal upon which the blade acts. The screen ring may be provided with a radial flange 18 95 to enable it to be detachably mounted upon the diaphragm plate 14, or on a plate 19 to which the fixed beaters 3 are attached.

The blade may be of channel section with the open part 20 of the channel as the leading side, and the depth of the channel may increase progressively from the root to the tip. Also the blade, and particularly the bottom wall of its channel would be curved 100 backwardly of its direction of rotation (indicated by the arrow) in the manner of a centrifugal fan blade. To give stiffness to the blade at the root, the side flanges of the

channel may be extended on each side of the portion forming the base of the channel, and/or there may be a stiffening web 21 behind it, and a laterally projecting flange or 5 base plate 22 may be provided at the base to enable the blade to be secured radially to the hub member 12 or the like on the shaft 5 which carries it. One blade alone generally suffices, but two, three (as shown) or 10 more may be employed if desired.

In action, the pulverized coal passes through the aperture 10 from the pulverizing chamber into the fan chamber, and the rotating striker or blade 11 traverses the 15 outgoing stream and acts upon the heavier particles of coal, flinging them back into the mechanism within the pulverizing chamber.

With this arrangement a very simple and effective device is provided for rejecting the 20 heavier particles of fuel and for returning them into the pulverizing mechanism for further treatment, whilst the construction employed is initially inexpensive and also cheap to renew. Furthermore, the use of baffles or other devices which would obstruct the outflow of the finely pulverized material is avoided.

What I claim as my invention and desire to secure by Letters Patent of the United 30 States is:-

1. A pulverizing apparatus comprising a casing having a centrally located outlet, impact members mounted to revolve substantially concentrically with the outlet, means 35 for introducing air and material to be pulverized to the peripheral zone surrounding the impact members, means to move the air and pulverized material towards the outlet, and radially projecting rejector blades

mounted to revolve close to the outlet, each 40 of which has an open ended substantially radial channel which slopes inwardly and is arranged to scoop coarse material from the air current passing the blades and hurl it inwardly towards the impact members. 45

2. A pulverizing apparatus comprising a casing having an inlet for air and coarse material and a centrally located outlet, impact members revoluble about the outlet to pulverize the material fed thereto, and a radially projecting rejector blade mounted to revolve close to the outlet and scoop coarse particles from the air current, said blade having a channel which faces in the direction of revolution and which increases in 50 depth from its inner to its outer end.

3. A rejector for use in a pulverizing apparatus comprising a channel shaped member provided with a laterally projecting base plate integral therewith arranged to be secured to a rotatable shaft, the channel of said member being open at its outer end so that material caught thereby may be hurled outwardly therefrom. 60

4. A rejector for use in a pulverizing apparatus comprising a channel shaped member adapted to revolve and scoop coarse material from an air current which is provided with a laterally projecting base plate arranged to be secured to a rotatable shaft, 70 the channel shaped member being so shaped that the bottom of the channel inclines backwardly with respect to a radial line and its direction of revolution.

In testimony whereof I have signed my 75 name to this specification.

CHARLES EDWARD BLYTH.
